UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

TUMBLER LOCK

Application filed January 13, 1926. Serial No. 80,992.

This invention has for its object to effect certain improvements in the art of manufacturing tumbler locks whereby the lock parts may be inexpensively manufactured of such uniformity that they are interchangeable and so accurately proportioned that, when assembled, the tumbler ends lie flush with the cylindrical surface of the lock cylinder, making unnecessary the usual expensive hand operation of filing the tumblers flush with the lock cylinder and obviating damage to the lock cylinder incident thereto.

More or less hand work and machining has heretofore been necessary in the manufacture of tumbler locks with the result that slight variations were unavoidable and, notwithstanding the exercise of the greatest care, some hand filing of protruding tumbler ends was necessary to permit the lock cylinder to snugly fit within the bore of the lock-case and work without catching. This hand filing has constituted an important item in the cost of manufacture of such locks and the roughened surfaces of the tumbler ends and of the lock cylinder due thereto have been objectionable both on account of the unsightly appearance of otherwise well-executed work and on account of impairment of the smooth working conditions of the locks.

With this invention machining and hand work are eliminated, avoiding the objections above noted, reducing the cost of manufacture, and improving the appearance as well as the smooth operation of the locks.

Another object of the invention is to so design the lock cylinder as to make it suitable for production by die casting whereby the desired uniformity of dimensions may be obtained and still afford sufficient strength.

Another object of the invention is to provide a lock with a lock cylinder of frangible material and so constructed that, upon an attempt to force the lock, it will fracture without releasing its locking engagement and its fractured state will baffle further attempts.

With the above and other objects in view 50 the invention consists in the tumbler lock

and method of producing same as herein claimed and all equivalents.

Referring to the accompanying drawings in which like characters of reference indicate the same parts in different views.

55

Fig. 1 is a longitudinal sectional view of a lock cylinder with its key and tumblers constructed in accordance with this invention;

Fig. 2 is a detailed view of a set of standardized interchangeable tumblers therefor;

Fig. 3 is a front view of the lock cylinder;

Fig. 4 is a transverse sectional view thereof on the plane of line 4-4 of Fig. 1;

Fig. 5 is a bottom view of the lock cylinder;

60

Fig. 6 is a transverse sectional view on the plane of line 6-6 of Fig. 5, and

Fig. 7 is a sectional view of the lock containing such lock cylinder and showing the fracture of the lock cylinder as when an attempt is made to force the lock.

In these drawings, 10 indicates a lock cylinder, which is die cast for uniformity of dimensions, particularly as to the distance y 75 between the bottom wall of the key slot 11 and the upper cylindrical surface of the lock cylinder.

The key 12 fitting in this key slot 11 and engaging the key bearing surfaces formed at the ends thereof is provided with the usual shoulders 13 to engage the stop shoulders 14 of the key slot to determine the operative position and its serrated upper edge forms key bits 15 of various heights, where the usual regularly spaced slide tumblers 16 engage with spring pressure holding the key seated on said key bearing surfaces.

As it is not feasible in a die casting to make the tumbler slots separate, a longitudinally extending diametrical cored slot 17 is formed through the lock cylinder with opposite grooves 18 in its side walls, within which the tumblers slide. The tumblers have openings 19, through which the key passes, as usual, and in order that they may bear with pressure on the serrated edge of the key, each is provided with a spring 20 housed within the cylinder in cylindrical recesses 21 and engaged by an outwardly projecting arm 22. To

80

85

90

95

100

5 avoid weakening the structure, the several
10 spring recesses 21 are arranged alternately
on opposite sides of the opening 17 and said
recesses extend in one direction to the sur-
face of the cylinder. In order to position
15 the spring 20 as close as possible to the center
line of the tumbler slide, its recess 21 is made
to open directly into the opening 17 and this
materially reduces the length of the guide
20 groove 18 on this side of the tumbler, but
compensation is provided for the interrup-
tion of the guide groove 18 by extending the
arm 22 into a guide groove 23 in the wall of
25 the recess, thus giving the tumbler slide op-
posite edge bearings at both ends to prevent
it from binding and also lateral bearings on
both sides of both ends and at both edges
30 to prevent lateral displacement by the pres-
sure of the key in passing therethrough. The
35 spring recesses 21 open directly to the opening
17 with parallel side walls and the springs 20
are seated in the closed ends thereof and are
located as close as possible to the edge of the
tumbler slides but are prevented from fric-
35 tional engagement therewith by pairs of beads
24 which project from the side walls of the
recesses for a short distance.

40 The spring pressure of the tumbler slides
upon the upper serrated edge of the key
45 forces the lower straight edge of the key into
bearing engagement with the bottom wall of
the key slot 11 at both ends thereof, which,
as before stated, is in predetermined definite
50 relation to the cylindrical surface of the lock
cylinder and forms the base line from which
55 the key bits 15 are dimensioned. The tum-
blers 16, preferably sheet metal stampings,
are formed in sets of different standardized
60 sizes, one set being shown in Fig. 2 as con-
sisting of the three sizes A, B and C. While
65 the outer dimensions of these tumblers are
the same and the size of the openings 19 are
the same, the distance from the upper end of
the opening to the upper end of the tumbler
70 differs in the different sizes, such distance
for tumbler A being indicated as a' , that
for tumbler B as b' , and that for tumbler C
as c' .

75 Not only are the effective dimensions of
the tumblers thus standardized and made
uniform for all tumblers of a given size, but
the bit heights of the key are also standard-
ized, a uniform dimension from the base line
80 formed by the bottom straight edge of the
key to the tumbler bearing surface of the key
bit being always the same for tumblers of a
given size. Thus all key bits for A tumblers
have the bit height dimension a complemen-
85 tary to tumbler dimension a' so that the two
together equal the dimension y of the lock
cylinder, and all key bits for tumblers B have
the dimension b complementary to tumbler
90 dimension b' so that the two together equal
the dimension y of the lock cylinder, and all
key bits for tumblers C have the dimension

95 c complementary to tumbler dimension c' so
that the two together equal the dimension y
of the lock cylinder. In this manner any
100 A tumbler, when assembled in position to en-
gage an A size key bit, will have both ends
exactly register with the surface of the lock
cylinder and, when the key bit formula is fol-
lowed in placing the tumblers in the lock
105 cylinder, perfect registration of all tumblers
necessarily follows and there is no occasion
110 for filing tumblers and for marring the
smooth surface of the lock cylinder in doing
so.

115 Such results are incapable of accomplish-
ment in quantity production with lock cylin-
ders made with machining or hand work so
that the die casting of lock cylinders is essen-
tial to the maintenance of the uniform dimen-
120 sions necessary for the purpose.

125 Although guards 25 may be used at the en-
trance to the key slot, as usual, to require a
key of particular sectional shape, provision
130 has been made to facilitate the entry of the
key by providing the key with a pointed end
having the downwardly directed cam surface
135 to guide it into proper bearing engagement
with the bottom of the key slot at the far end
of the opening 17 and with the upwardly
directed cam surface for lifting the tumblers
140 and, in order that the key may not bind by
being inserted in an angular position in-
fluenced by the pressure of the spring-pressed
tumblers, one or more bridges 26 are formed
145 across the opening 17 connecting with and
forming oblique extensions of the walls of
150 tumbler grooves 18, as best seen in Fig. 5. It
is found in practice that these bridges 26 may
be so arranged without interfering with the
155 coring of the lock cylinder die. The bridges
26 terminate just below the level of the bottom
160 of the key slot but serve to lift the key when
engaged by the downwardly directed cam on
the end of the key should the key be inserted
165 in an inclined position and thus prevent bind-
ing and facilitate the insertion of the key.
170 Also upper guide shoulders 27 are formed at
both ends of the key slot to insure the proper
seating of the key by their engagement with
175 a longitudinally extending shoulder 28 on the
key itself.

180 The lock cylinder of this invention may be
used in a lock-case of any type and may effect
a locking engagement in any well known man-
ner but one type of lock is shown in Fig. 7,
185 wherein the lock-case 29 forms a part of the
dead bolt of a transmission lock for automo-
biles, the lock cylinder 10 being confined
therein by a hard metal cap 34 and serving
190 to operate a spring-pressed locking bolt 30 by
having a wrist-pin or cam projection 31 on
its end engaging a slot in said locking bolt.
195 In this view is shown the protective feature
of the die cast lock cylinder of this invention
whereby the forcing of the lock is prevented
200 owing to the frangible nature of the die cast-
130

ing and the weakening thereof by the coring to produce the opening 17 with the tumbler grooves and the spring recesses. With the tumblers 16 engaged in the tumbler slots of the lock-case, as when the mechanism is locked, an attempt to force the lock by means of a tool such as a screw-driver 32 driven into the key slot of the lock cylinder and turned by means of a wrench 33, will cause the lock cylinder to fracture transversely at about the plane of the uppermost tumbler or the plane of the sectional view shown in Fig. 4. The loose upper end of the lock cylinder will then turn freely without affecting the lower portion of the lock cylinder, which remains locked by the tumblers to prevent the release of the mechanism controlled by the lock.

While the lower straight edge of the key and the bottom of the key slot against which it bears and is held by the pressure of the spring tumblers are defined as constituting the base or reference line from which the parts are dimensioned for accurate complementary matching the tumblers to the key bits, it is obvious that any other reference surfaces on the key and lock cylinder may be employed provided they are held in bearing contact by the pressure of the spring-pressed tumblers.

What I claim as new and desire to secure by Letters Patent is:

1. In a lock, a die cast lock cylinder having a longitudinally extending diametrical opening with grooves in its walls, tumbler slides fitting in said grooves across the opening, said opening and grooves so weakening the die cast lock cylinder that an attempt to turn it by force will cause it to fracture transversely along the plane of the first tumbler without disabling the locking engagement of the tumblers.

2. In a lock structure, a lock cylinder having a passageway therein for the reception of a key having bits of different predetermined heights, key guiding means in the cylinder passageway and located in a predetermined position with respect to the cylinder periphery, the cylinder being die cast in one piece to obtain uniformity in such positioning, and preformed spring pressed plate tumblers fitting in the lock cylinder and having surfaces adapted for engagement on the bits of a key inserted in the cylinder passageway, the key engaging surfaces of the tumblers being at different and predetermined distances from the tumbler ends, the predetermined distances between said key engaging surfaces and the ends of the tumblers and the heights of the corresponding key bits being equal to the distance from the cylinder key guiding means to the cylinder periphery, whereby when originally assembled and bearing on the bits of the key adapted for use with the cylinder all tumblers lie flush with the periphery of the lock cylinder so as to require no dressing.

3. A lock cylinder having a key slot for the reception of a key provided with a bottom straight edge and key bits on its top edge of different but standardized uniform heights, as measured from the straight edge of the key, the key slot being provided with a key bearing surface in predetermined relation with respect to the cylinder periphery and the cylinder being die cast in one piece to obtain uniformity, preformed spring pressed plate tumblers fitting in the lock cylinder and having openings through which a key passes when inserted in the key slot, said tumblers having different but standardized uniform dimensions from their openings to their ends, there being a companion complementary tumbler size for each bit size on the key to be used in the cylinder and the two together equaling the distance from the key bearing surface of the key slot to the periphery of the lock cylinder, whereby when originally assembled and bearing on the bits of the key adapted for use with the cylinder all tumblers lie flush with the periphery of the lock cylinder so as to require no dressing.

4. In a lock including a cylinder having a slot for the reception of a key having bits of different but uniform standardized heights, preformed spring pressed plate tumblers having bit bearing surfaces of different but uniform standardized sizes as measured from the bit bearing surfaces to the ends of the tumblers, there being a tumbler size complementary to each key bit size of the key adapted for use with the lock, and the aggregate dimensions of all complementary key bit sizes and tumbler sizes being equal, and key bearing means in the cylinder key slot and positioned from the wall of the lock cylinder the distance of said equal aggregate dimensions, whereby when the tumblers are originally assembled and bearing on the bits of the key adapted for use with the cylinder all tumblers lie flush with the periphery of the lock cylinder so as to require no dressing, said lock cylinder constituting a one piece die casting whereby said positioning of the bearing surface relative to the cylinder periphery is predetermined of a uniform standard.

In testimony whereof, I affix my signature.

EDWARD N. JACOBI.
